UNITED STATES PATENT OFFICE.

ALBERT D. FIELD, OF NEW YORK, N. Y.

ADJUSTABLE OR EXTENSION CURTAIN-POLE.

SPECIFICATION forming part of Letters Patent No. 378,087, dated February 21, 1888.

Application filed September 3, 1887. Serial No. 248,723. (No model.)

To all whom it may concern:

Be it known that I, ALBERT D. FIELD, of New York, in the county of New York and State of New York, have invented certain new and useful Improvements in Adjustable or Extensible Curtain-Poles; and I do hereby declare the following to be a full, clear, and exact description of the invention, such as will enable others skilled in the art to which it applies to make and use the same.

My invention relates to an improvement in extensible curtain-poles.

The objects of my present invention are to provide a curtain-pole that may be extended at one or both ends and be adapted to lie in fixed brackets or be held in position by socket ends, and, further, to produce a substantial as well as handsome device of the character indicated, constructing it so as to admit of rapid and continuous production by machinery, thus affording a durable and elegant article for the purpose designated at a low initial cost.

With the attainment of the above-named objects in view, my invention consists in certain features of construction and combinations of parts that will be hereinafter described, and pointed out in the claims.

Referring to the drawings, making a part of this specification, Figure 1 is a view of the curtain-pole with its bracket-lugs shown in connection with a fixed bracket. Fig. 2 represents the same style of pole provided with a modified form of bracket-lug, which latter is made of wire, while the preferred form is constructed of sheet metal. Fig. 3 is a view in elevation of the curtain-pole and attached parts to fit it for support at any desired length upon a pair of fixed brackets. Fig. 4 is a similar view of one end of a curtain-pole that is adapted to be supported by socket-rings that engage the ends of the pole. Fig. 5 is a view of the center slide-pipe or hollow rod, an attached centering guide-block in position on the rod, and a bracket-lug made of sheet metal, showing plan of securing these pieces together. Fig. 6 is a longitudinal section of the curtain-pole, as shown in Fig. 1. Fig. 7 represents a longitudinal section of the curtain-pole shown in Fig. 2. Fig. 8 is a modified form of a pole-supporting bracket that is made of two pieces of wire.

The curtain-pole complete is composed of a central section, A, and two sliding tubular sections, A', which are made to fit upon the center-piece. The central portion, A, is made, preferably, of wood in cylindrical form, and has an axial perforation, a, made throughout its length. The longitudinal hole a is produced by boring a solid stick, or it may be made in the form of a half-circular groove in two corresponding half-cylinders that are afterward glued or otherwise attached together to form a round pole with a longitudinal axial hole in it.

In the hole a two extension-rods, C, are fitted to slide freely and extend at each end. This connection should be such as to avoid improper looseness. The rods C are preferably constructed of sheet metal, such as tin-plate, as tin-covered sheet-iron is not liable to rust, and is preferred on this account. The hollow rods are made of the sheet metal by proper means, and upon one end of each extension-rod C a round block or short cylinder of wood, D, is secured, which are intended to form guide-blocks to keep the outer ends of the rods C steady when they are pulled out to sufficiently extend the length of the pole.

The guide-blocks D are of a proper diameter to enter and fit neatly within the tubular sections A' of the pole A and slide in contact with the interior surface of said sections. Each of the sections A' is provided with a longitudinal slot, b, which extends nearly to each end of the section. The slots are designed to receive the bracket-lugs E, (shown in Fig. 5,) which are made of sheet metal stamped out and folded together so as to produce clasps at their inner ends, that conform to the surface of the extension-rods C, upon which they are mounted, and are secured in place by cutting two lips loose on three sides at a proper point on the cylindrical wall of the sheet-metal hollow extension-rods C, and turning the same at right angles to the surface of the rods to produce a projecting ear, c, near the outer end of each rod.

The guide-blocks D are placed upon the hollow rods C, outside of the ears c, and are of such a relative length as to allow a short end of the rod to project beyond each block, the blocks being held firmly against the bracket-lugs, which are in contact with the ears c, by

- spreading the sheet metal of the rod outwardly to act as rivet-heads. In a similar manner the wire bracket-lugs shown in Fig. 2 are secured in position upon the rods C, when that 5 form of lug is to be employed, to afford a means of attachment of the curtain-pole to the supporting-brackets. The wire bracket-lugs H have eyes turned on each end at right angles to each other, the larger eyes, H', being made 10 to fit upon the rods C, as above stated, while the smaller eyes, H², that are turned up on the projecting ends of the wire brackets H, are intended to engage the pintles e formed on the supporting-brackets I. (See Fig. 7.) The 15 bracket shown in Fig. 1 is preferably made of cast metal, and may be given any ornamental form desired. It is essential, however, that the upper edge of its outwardly-projecting body be provided at proper points with 20 the pintles e, and also be curved or bent at the outer end to afford a cradle or support for the body of the curtain-pole, as shown in Fig. 1. The flat sheet-metal bracket-lugs E are perforated at a suitable distance from their outer 25 end to afford a means of engagement with the pintles e of the brackets I, as shown in Fig. 6. In case a cheaper form of supporting-bracket is preferred the style shown in Fig. 8 may be adopted.
- 30 The supporting-bracket J (see Fig. 8) is composed of a piece of wire, f, which has one end, g, flattened and bent at an angle to the round body provided with a hole for accommodation of a screw to affix the bracket-foot 35 in position to the window-casement. The opposite end, h, of the piece f is bent at about the same angle as the lower end, g, and in an opposite direction.
- A straight piece of wire K is flattened to 40 produce a rounded outer end, i, that is perforated to be placed over the upper free end, h, of the piece f, and as the opposite end of the straight piece K is threaded to produce a gimlet-pointed screw thereon, if the piece K is 45 first screwed into the window-frame at right angles to it and the end h of the piece f inserted through the perforated outer end, i, and the lower end of f secured by screwing it fast to the frame by its lower end, g, it will be seen 50 that the piece f will form a diagonal brace to the projecting round wire rod K to give it stability sufficient to carry the curtain-pole and attached drapery, the bracket-lugs or eyes of the pole being placed upon the upwardly-projecting ends h of the wire brackets H.
- 55 When it is preferred or the situation requires that the curtain-poles should be supported in place without the use of the brackets such as have been previously described, 60 the poles may be held in position by the sockets or cupped flanges L, (see Fig. 4,) which are preferably cut and stamped into form by dies from sheet metal, and have perforated centers to receive the ends of the curtain-pole, 65 these annular cupped flanges having spaced screw-holes made near their peripheral edges to receive screws, by which they are attached

in proper position to opposite points on the window-casements.

In case the curtain-pole is to be supported 70 in place by the socket-flanges L, or be simply laid on the cast-brackets previously described, the bracket-lugs may be dispensed with and the tubular sections A' of the pole be held in sliding connection with the center portion, A, 75 by set-screws m, which are inserted through the longitudinal slots formed in the sheet-metal sections A' into the wooden piece A.

In the construction of the improved pole and 80 brackets herein shown two extension-rods, C, may be employed to afford a means of adjusting the length of the pole to suit the varying widths of windows, or the adjustment for length may be made at one end only and but one extension-rod used.

If a great range of adjustment is required, 85 this can best be afforded by the use of an adjusting device at each end of the pole.

When the poles are mounted upon brackets, 90 their ends may be given an ornamental finish by the adjustment upon them of the globular ornaments shown, these spheres being preferably struck up out of sheet metal in two pieces, which are joined at their edges, and the globes secured to a socket that affords a means of attachment to the ends of the poles.

95 Hard wood is preferred from which to construct the central portion of the curtain-poles, and this may be stained and finished in any style desired, or the wood may be covered with plush of any preferred color to match curtains, and thus produce beautiful effects at a moderate cost. The metal portions are preferably made of sheet-brass which is lacquered to give it a rich golden appearance and prevent tarnishing of the bright metallic surface of these 100 portions of the device. The brackets may also be gilded or bronzed to render them harmonious in finish with the other portions of the metal work or trimmings of the curtain-pole.

105 I do not desire herein to broadly claim the use of a wooden center-piece and tubular end sections that slide on it, as I have already shown a method of construction of a solid pole and sliding sections in patent of record number 277,258, dated May 8, 1883; but,

110 Having fully described my invention, what I claim as new, and desire to secure by Letters Patent, is—

115 1. In an adjustable curtain-pole, the combination, with a hollow central section, of one or more tubular sections adapted to be moved endwise on the central section, and an extension-rod adapted to slide in the central section and form a bearing for one of the tubular sections, substantially as set forth.

120 2. In an adjustable curtain-pole, the combination, with a central section that is axially perforated, an extension-rod, and a guide-block, of a tubular section placed upon one end of the central hollow section and adapted to move thereon endwise and on the guide-block, substantially as set forth.

125 3. In an adjustable curtain-pole, the combi-

nation, with a central section that is perforated axially, one or more slotted tubular end sections, and an extension-rod that slides in the central section, of a guide-block to loosely fit the hollow end section, and a bracket-lug affixed to the extension-rod and adapted to slide in the longitudinal slot of the tubular end section, substantially as set forth.

4. In an adjustable curtain-pole, the combination, with a hollow central section, and a slotted tubular end section, of an extension-rod carrying a guide-block and a bracket-lug and adapted to be moved in the central section independently of the sliding movement of the adjustable tubular end section, substantially as set forth.

5. In an adjustable curtain-pole, the combination, with a hollow center section and a tubular section adapted to slide on the central section, of an extension-rod carrying a guide-block and a bracket-lug and adapted to slide in a longitudinal slot formed in the tubular end section to afford a means of adjustment

for the bracket-lug independent of the central section or tubular end section of the curtain-pole, substantially as set forth.

6. In an adjustable curtain-pole, the combination, with a longitudinally-perforated central section, an extension-rod, and a guide-block affixed to the end of the extension-rod, of a tubular end section slotted longitudinally and brackets that are adapted to support the curtain-pole, substantially as set forth.

7. The combination, with a central section, an extension-rod mounted therein and provided with a guide-block, and a tubular end section secured to said central section and guide-block, of socket-flanges placed on the ends of the pole, substantially as set forth.

In testimony whereof I have signed this specification in the presence of two subscribing witnesses.

ALBERT D. FIELD.
